UNITED STATES PATENT OFFICE.

FRED A. MANSFIELD, OF PHILADELPHIA, PENNSYLVANIA.

DESIGN FOR A LAMP-POST.

SPECIFICATION forming part of Design No. 33,256, dated September 25, 1900.

Application filed July 5, 1900. Serial No. 22,638. Term of patent 14 years.

To all whom it may concern:

Be it known that I, FRED A. MANSFIELD, a citizen of the United States, residing at Philadelphia, in the county of Philadelphia and State of Pennsylvania, have invented and produced a new and original Design for a Lamp-Post, of which the following is a specification, reference being had to the accompanying drawing, forming part hereof, which shows a representation of a lamp-post designed in accordance with my present invention.

As shown in the drawing, the leading or material feature of my design consists of a base portion provided near its top with a flange or projection, above which rises the post, which has a generally-tapering form and is provided at substantially its middle with an enlargement of the general configuration shown.

In the drawing, *a* is the base portion, which is provided near its top with the flange or pro-

jection *a'*. Rising from the flange *a'* is the post portion *b*, which is of a generally-tapering form, provided at substantially its middle with an enlargement *b'*. The post portion *b* is also provided longitudinally with depressions *b*², which add to the ornamentation of the post. 25

Having thus described my invention, what I claim as new, and desire to secure by Letters Patent, is—

The design for a lamp-post substantially as herein shown and described. 30

In testimony whereof I have signed my name to this specification in the presence of two subscribing witnesses.

FRED A. MANSFIELD.
